Primary Examiner — Michael C Stout*Assistant Examiner* — Fitzgerald L Butac(74) *Attorney, Agent, or Firm* — Fitch, Even, Tabin & Flannery LLP(57) **CLAIM**

We claim the ornamental design for a vehicle driving robot, as shown and described.

DESCRIPTION

FIG. 1 is a front, left, top perspective view of a vehicle driving robot, showing our new design;

FIG. 2 is a rear, left, top perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof,

FIG. 8 is a left side elevational view thereof; and,

FIG. 9 is an enlarged cross-sectional view thereof taken along line 9-9 in FIG. 5, with only the sectioned portions thereof illustrated.

The broken lines show portions of the vehicle driving robot which form no part of the claimed design.
